UNITED STATES PATENT OFFICE.

ARSAN ANTONY FAUCHER, OF MILAN, WISCONSIN.

WRENCH FOR NUT-LOCKS.

1,058,295.

Specification of Letters Patent.

Patented Apr. 8, 1913.

Application filed September 13, 1912. Serial No. 720,299.

To all whom it may concern:

Be it known that I, ARSAN A. FAUCHER, a citizen of the United States, residing at Milan, in the county of Marathon and State of Wisconsin, have invented certain new and useful Improvements in Wrenches for Nut-Locks, of which the following is a specification.

This invention relates to improvements in wrenches, more particularly to a special form of wrench designed to release a nut from its locking mechanism and then removing the nut, and has for one of its objects to provide a simply constructed device which effectually accomplishes the desired results.

Another object of the invention is to provide a simply constructed wrench which may be employed for the specific purpose above noted and also employed as an ordinary key wrench.

With these and other objects in view, the invention consists in certain novel features of construction as hereafter shown and described and then specifically pointed out in the claim.

Figure 1 is a plan view of the improved wrench with the releasing lever disposed in open position. Fig. 2 is a side elevation 30 with the head portion in section on the line 2—2 of Fig. 1, and with the releasing lever in closed position. Fig. 3 is a detached perspective view of the releasing lever and its head.

The improved wrench comprises a stock or handle 10 having a hollow nut engaging socket 11 at one end. The socket is provided in its upper face with a relatively large opening 12. Spaced above the socket is a plate 13 which is connected at its sides to the body of the socket leaving the ends unconnected and forming a chamber above the socket. The plate 13 is provided with an opening 14 which corresponds to and registers with the opening 12 of the socket. Mounted for rotation through the apertures 12—14 is a cylindrical shell 15 having a plurality of recesses 16 in its lower edge whereby a plurality of teeth-like projections 17 are formed, the apertures 12—14 thus

serving as bearings to support the shell 15. Arranged to swing upon the outer face of the stock 10 is a releasing lever 18 which projects at one end into the chamber between the plate 13 and the socket 11 and is divided into coacting arms 19 which bear around the shell 15 from opposite sides and are riveted or otherwise secured to the shell as shown at 20. By this simple means the shell may be oscillated by moving the lever 18 toward or away from the stock 10. The stock 10 is provided with a stock 21 against which the lever 18 engages while in closed position to limit its movement in one direction.

The improved wrench is designed to release the locking pawls of a lock nut to enable the nut to be removed and after the pawls are released the socket 11 is utilized to unscrew the nut and remove it from the bolt. The improved wrench may likewise be employed to apply the nut to the bolt as will be obvious.

The specific form of nut to which the improved wrench is more particularly applicable is illustrated in an application for patent recently filed and includes a plurality of pawls between which and the bolt the portions 17 of the shell 15 are designed to engage when the lever 18 is in the position shown in Fig. 1, and then when the lever 18 is moved over into parallel relations to the stock 10 with the free end against the stock 21, the rotation of the shell caused by this movement will move the locking pawls outwardly and thus release them from the bolt and permit the nut to be detached, the lever 18 being held in parallel relations to the stock and against the stock 21 during the retrograde movement of the nut.

It will be noted that the shell 15 together with its "teeth" 17 is located within the inner end of the shell 11 leaving the lower portion unobstructed. By this means the improved wrench may be employed as a key wrench on an ordinary nut.

Having thus described my invention, what I claim is:

A wrench comprising a nut engaging socket having a bearing opening through its outer end, an operating lever arm extending

95

100

2
from the socket, a shell mounted to oscillate through the bearing opening of said socket and extending into the socket a less distance than the depth of the socket, and adapted to engage around a bolt externally of the nut over which the socket is located, said shell having a plurality of pawl engaging projections in its inner edge, and a trip lever

connected to said shell externally of the socket.

In testimony whereof I affix my signature in presence of two witnesses.

AESAN ANTONY FAUCHER. [L. s.]
